US00D850075S

(12) **United States Design Patent** (10) Patent No.: **US D850,075 S**
(45) Date of Patent: ** *Jun. 4, 2019

(54) **SHOE**(71) Applicant: **NIKE, Inc.**, Beaverton, OR (US)(72) Inventors: **Fidencio Campos**, Dallas, OR (US);
Troy C. Lindner, Portland, OR (US);
Tetsuya T. Minami, Portland, OR (US)(73) Assignee: **NIKE, Inc.**, Beaverton, OR (US)

(*) Notice: This patent is subject to a terminal disclaimer.

(**) Term: **15 Years**(21) Appl. No.: **29/669,729**(22) Filed: **Nov. 9, 2018****Related U.S. Application Data**

(63) Continuation of application No. 29/557,831, filed on Mar. 11, 2016, which is a continuation-in-part of application No. 29/542,737, filed on Oct. 16, 2015, now abandoned, which is a continuation of application No. 29/519,930, filed on Mar. 9, 2015, now abandoned.

(51) **LOC (11) Cl.** ..... **02-04**(52) **U.S. Cl.**USPC ..... **D2/947****(58) Field of Classification Search**

USPC ..... (57)

CLAIM

The ornamental design for a shoe, as shown and described.

DESCRIPTION

FIG. 1 is a front perspective view of a shoe showing our new design;

FIG. 2 is a side view thereof;

FIG. 3 is an opposite side view thereof;

FIG. 4 is a front view thereof; and,

FIG. 5 is a rear view thereof.

The broken lines depicting the remainder of the shoe show features that form no part of the claimed design.

1 Claim, 5 Drawing Sheets# US D850,075 S
